C. SCHAER

AIR COMPRESSOR

Filed Feb. 26, 1926

Charles Schae
INVENTOR

BY
Jeffrey Kimball & Appleton
ATTORNEY

UNITED STATES PATENT OFFICE.

CHARLES SCHAEER, OF LANGENTHAL, SWITZERLAND, ASSIGNOR TO BUSCH-SULZER BROS.-DIESEL ENGINE CO., OF ST. LOUIS, MISSOURI, A CORPORATION OF MISSOURI.

AIR COMPRESSOR.

Application filed February 26, 1926, Serial No. 90,768, and in Switzerland March 5, 1925.

This invention relates to air compressors and in particular to an arrangement of air pumps for use in connection with two-cycle internal combustion engines, the purpose of the invention being to provide a simplified and improved arrangement of supercharging and scavenging air pumps whereby, among other things, supercharging air may be supplied to the engine cylinder from one or both of the pumps as desired. The invention further contemplates the provision of a piston cross-head for one of the said pumps, which will serve as the low pressure piston for a multiple-stage injection air compressor where such is used.

The present invention therefore consists in the combination and arrangement of parts hereinafter described, whereby the several air supplies referred to are obtained in a more economical and generally advantageous way than heretofore.

In the accompanying drawing is illustrated, in part diagrammatically, a preferred embodiment of the invention.

Indicated generally by the reference numeral 1 is an internal combustion engine cylinder in axial section, having in its head the fuel injector 2. The cylinder wall is provided with the exhaust port 3 and the air inlet ports 4 and 5. The particular arrangement of the ports illustrated forms no part of the present invention, being fully described in the specification of the pending application of Charles Schaeer, Serial No. 55,233, filed September 9, 1925, for two-cycle engines. The advantages of such arrangement will be readily apparent to those skilled in the art and particularly so in conjunction with the present invention. For a complete understanding of the latter, however, it will be sufficient to say that low pressure air for scavenging purposes is supplied through the port 4 from the receiver 6 when the port is uncovered by the descending piston and supercharging air is supplied through the port 5 from the pipe connection 7 under the control of the mechanically operated valve 8.

Considering now the adaptation of the present invention to an arrangement of this kind, it will be seen that there are provided three coaxial cylinders 9, 10 and 11, having a common piston rod 12, spaced pistons 13, 14 and 15, and common actuating means

of any desired form, herein comprising the crank 16 and connecting rod 17.

The cylinder 9 and piston 13 constitute the low pressure unit of a multiple-stage air compressor which furnishes the injection air through suitable pipe connections to the injector 2.

The cylinder 10 and piston 14 constitute a double-acting scavenging pump, the cylinder at both sides of the piston having valved outlet connections with the receiver 6 and valved inlets from the suction head 18. For clearness, the valves and inlet and exhaust passages herein are indicated diagrammatically.

The cylinder 11 and piston 15 constitute a double-acting supercharging pump which supplies the supercharging high pressure air to the pipe connection 7 and thence the port 5.

The suction side of the supercharger is suitably connected to a suction head 19, through a three-way valve 20, one side of which may be connected at will with the outlet side of the scavenging pump. When so connected supercharging air will be supplied to the cylinder from both the supercharging pump and the scavenging pump.

From the arrangement of air compressor unit, scavenging air pump and supercharging air pump above described it will be apparent that the engine can be kept supplied with the necessary quantities of air at the desired pressures in a very efficient manner and without the necessity for providing independently operated pumps or compressors for any of the purposes to be served.

It will be understood, of course, that the construction and arrangement of the various parts are subject to variation without departing from the scope of the following claims.

I claim:

1. An air supply system for two-cycle internal combustion engines comprising two double acting pistons arranged in tandem and adapted to supply respectively supercharging and scavenging air and a cross-head for the piston of the scavenging air pump comprising the low pressure piston of a multiple-stage injection air compressor.

2. An air supply system for two-cycle internal combustion engines comprising a pair of tandem arranged pumps adapted to sup-

- ply respectively supercharging and scaveng-
ing air and valve connections whereby super-
charging air may be supplied to the engine
from the one or both of the pumps at will.
5. An air supply system for two-cycle in-
ternal combustion engines including a low
pressure scavenging air pump and a piston
crosshead therefor comprising the low pres-
sure piston of a multiple-stage injection air
10 compressor.
4. An air supply system for two-cycle in-

ternal combustion engines comprising a
supercharging air pump having a double
acting piston in tandem with a second double
acting piston for supplying scavenging air 15
and a cross-head for the piston of one of
said pumps comprising the low pressure pis-
ton of a multiple-stage injection air com-
pressor.

In testimony whereof, I have signed this 20
specification.

CHARLES SCHAEER.
